 Esq.; Dobbin IP Law, P.C.

(57) **CLAIM**

The ornamental design for a rack, as shown and described.

DESCRIPTION

FIG. 1 is a top plan view of the claimed rack.
 FIG. 2 is a side elevation view of the rack of FIG. 1.
 FIG. 3 is a perspective view of the rack of FIG. 1.
 FIG. 4 is a left perspective view of the rack of FIG. 1; and,
 FIG. 5 is a right perspective view of the rack of FIG. 1.
 The broken lines show portions of the rack that form no part
 of the claimed design.

1 Claim, 5 Drawing Sheets
